UNITED STATES PATENT OFFICE.

GEORGE O. WHITNEY AND ARTHUR W. IDE, OF BRAINERD, MINNESOTA.

STEAM STOOL-STERILIZER.

1,325,429.

Specification of Letters Patent. Patented Dec. 16, 1919.

Application filed November 13, 1917. Serial No. 201,819.

To all whom it may concern:

Be it known that we, GEORGE O. WHITNEY and ARTHUR W. IDE, citizens of the United States, residing at Brainerd, in the 5 county of Crow Wing and State of Minnesota, have invented certain new and useful Improvements in Steam Stool-Sterilizers; and we do hereby declare the following to be a full, clear, and exact description of the 10 invention, such as will enable others skilled in the art to which it appertains to make and use the same.

The invention relates to a stool sterilizer for railway coaches and various other places. 15 The object of this invention is primarily to furnish means whereby all soil from the closets of railway cars may be sterilized and thereby rendered free from infectious disease organisms as unsterilized excretions 20 from persons suffering from typhoid fever and other diseases deposited along railway right of way may be washed by rain into nearby wells or streams and pollute the water supply of farms, towns and cities and expose 25 public health to grave danger from such source of contamination. This invention is designed to furnish a practical method of correcting this evil and rendering this material sterile and free from all living 30 organisms and in this manner the present faulty method of disposal of sewage may be corrected and the public health conserved.

A further object of the invention is to furnish 35 means by which the closets of trains may be kept open and ready for use at all times and to enable the discharges from the plumbing of coaches to be caught in a suitable receptacle located beneath the car and adapted 40 after sterilization to be dumped at will by an attendant. This will obviate the danger of contamination of stations, platforms and places where employees are required to work and it will reduce the amount 45 of care and work which the attendant now necessarily gives to these toilets. A further object of the invention is to equip the stool sterilizer with an indicator so that the attendant, instead of frequently locking and 50 unlocking the doors of the toilets, may observe the indicator and dump the tank when necessary at the proper place.

It is also an object of the invention to enable 55 the soil to be saved and used for fertilizer and to provide a construction not only adapted for use in railway coaches and other

public conveyances, but which may be advantageously employed in hospitals and other places where patients suffering from diseases are congregated and where excretions, unless properly sterilized, are a source of danger to the public.

With these and other objects in view, the invention consists in the construction and novel combination of parts hereinafter fully 60 described, illustrated in the accompanying drawings and pointed out in the claim here-to appended; it being understood that various changes in the form, proportion, size and minor details of construction, within 65 the scope of the claim, may be resorted to without departing from the spirit or sacrificing any of the advantages of the invention.

In the drawings:

Figure 1 is a longitudinal sectional view of a steam sterilizer constructed in accordance with this invention.

Fig. 2 is an end elevation of the same.

Fig. 3 is a horizontal sectional view.

Fig. 4 is a detail view of the dumping lever.

Fig. 5 is a side elevation of the same and the rotary valve member.

Fig. 6 is a detail sectional view illustrating the construction of the indicator.

Like numerals of reference designate corresponding parts in all the figures of the drawings.

In the accompanying drawings, in which 90 is illustrated the preferred embodiment of the invention, the steam sterilizer comprises in its construction a substantially oblong tank 1 designed to be located beneath the water closet of a car. The tank 1 is provided in its top wall with an opening 1^a to receive the lower end 1^b of a stool of any well known or preferred construction. The stool connection may be at any convenient point through the top of the tank and the 95 latter may be of any desired size to suit requirements and, while the device is especially adapted for use on cars and other conveyances, it may be advantageously employed at all places where it is desirable or 100 necessary to sterilize the excretions or to save the same for use as fertilizer. The tank has a tapered end portion 2 which is provided with an outlet 3 at which is mounted a valve casing 4 of a rotary valve member 105 5. The valve casing, which is substantially cylindrical, is open at the bottom and its in-

terior is tapered to provide a tapering valve chamber 6 for the tapered valve member 5. The valve member 5 consists of a tapered shell having a horizontal top wall 7 and 5 provided with a vertical outlet opening 8 adapted to be carried by the rotary movement of the valve member into register with the outlet 3 of the tank 1. The lower end of the rotary valve member 5 is open for the 10 discharge of the contents of the sterilizer tank.

The valve member 5 is provided at the top with a central vertical stem 9 extending through a central opening 10 in the top wall 15 of the valve casing and provided with a head 11 at the upper end. The lower portion of the stem receives a coiled spring 12 interposed between the top of the valve casing and a collar 13 which fits against a pin 14 20 to form a stop for the upper end of the coiled spring. The coiled spring is adapted to urge the valve member upwardly into tight engagement with the valve casing to prevent any leakage from the sterilizer tank 25 when the valve is closed.

The upper portion of the valve stem is mounted in a stand 15 and the head 11, which is located at the top of the stand, is bifurcated at 16 for the reception of a lever 30 17 pivoted by a pin 18 or other suitable fastening device in the slot or bifurcation and having a projecting heel portion 19 adapted to be swung into engagement with the rear wall 20 of the bifurcation 35 when the lever is raised from a depending vertical position to a horizontal position. The top of the stand is provided with stops 21 for limiting the horizontal swing of the head 11 and it has a central notch 22 adapted 40 to receive the lever when the same is swung downward to the position shown in Fig. 5. The lever operates as a gravity lock for holding the valve in its closed position and when the lever is in engagement with 45 the notch the opening 8 of the rotary valve member is out of register with the outlet of the tank.

The valve casing is provided with a steam chamber 23 extending around the valve casing 50 from one side of the same to the other thereof and having an outlet 24 at one side and connected at the opposite side with one end 26 of a steam sterilizer pipe 27 which is connected with a suitable source of steam 55 supply (not shown). The steam sterilizer pipe 27 is preferably D-shaped cross sectionally as clearly shown in Fig. 1 of the drawings so as to lie flat upon the bottom of the sterilizer tank and it is provided with 60 a series of transversely disposed loops or convolutions made up of transversely disposed parallel portions and reversely arranged connecting bends. The pipe forms a substantially serpentine passage for the 65 steam which sterilizes the contents of the

tank and which, by passing around the valve casing and the rotary valve member, will prevent the latter from freezing.

The tank is provided at the end opposite that at which the outlet is arranged with 70 clean out openings 28 normally covered by doors or plates 29 having cupped centers 30 which are engaged by the terminals 31 of a clamp 32 mounted on a threaded stem 33 and engaged by a nut 34 of the said stem. 75 The stem is suitably fixed to and projects horizontally from the center of the adjacent end of the casing 1 and its outer portion is threaded for the reception of said nut. The doors are adapted to be removed 80 and a hose inserted in the casing for thoroughly washing the same when necessary.

The casing has a vent pipe or tube 35 which is designed to extend through the roof of a car or to any other convenient 85 point wherever installed. The vent pipe will carry off the fumes and also the steam or vapor generated by the steam coil in the sterilizing of the contents of the tank. The tank is also equipped with an indicator comprising a float 36 operating within a perforated casing 37 and connected with one arm of an intermediately pivoted lever 38 which has its other arm connected with one end of a flexible connection 39 such as a bronze 95 wire or the like. The flexible connection 39 extends through a tube 40 to an indicator casing 41 and is attached to and arranged on a grooved pulley 42. The grooved pulley, which is mounted on a suitable shaft or 100 spindle 43, is also connected to one end of a coiled spring 44 which urges the pulley in one direction for carrying a hand or pointer 45 to a point marked E for indicating when the tank is empty. The indicator casing is 105 provided with a support 46 to receive the spindle or shaft and it may have a slotted disk or dial 47. The disk or dial has an arcuate slot 48 located in advance of the pointer or indicator for exposing the same 110 and the ends of the slot are preferably marked E and F for indicating when the tank is empty or full. The indicator is located at a convenient point and as the tank fills the float will rise and through the connection between the lever and the shaft will swing the indicator hand or pointer away from the point E. The porter or attendant may readily ascertain the condition of the tank and empty the same at the proper 115 place for the disposal of the contents. As the contents are confined until disposed of in this manner the toilets may be left open at stations insuring greater comfort and convenience for the traveling public, and at 120 the same time effectually protecting the public from the contamination resulting from the water closets in use on ordinary trains. 125

What is claimed is:

A sterilizer of the character set forth in 130

cluding a tank having a tapered end provided with an outlet opening, a valve casing secured to said tapered end across the outlet opening therein and having in its 5 side an intake opening registering with said outlet opening and having a discharge opening in its lower end, a valve rotatably mounted in said casing and having an inlet opening in its side and an outlet opening 10 in its lower end, means by which the valve may be operated, a steam jacket carried by the valve casing and provided with inlet and outlet openings, and a steam pipe arranged within the casing and having its in-

let end passing through the side wall of the 15 casing and having its discharge end communicating with the inlet opening of said jacket, said steam pipe being composed of transverse loops extending back and forth across the tank and throughout the entire 20 length of the tank.

In testimony whereof we affix our signatures in presence of two witnesses.

GEORGE O. WHITNEY.
